UNITED STATES PATENT OFFICE.

COSIMO MITRANO, OF BROOKLYN, NEW YORK.

DESIGN FOR A LOCKET, FOB, OR SIMILAR ARTICLE.

52,338.

Specification for Design.

Patented Aug. 27, 1918.

Application filed April 25, 1918. Serial No. 230,847. Term of patent 3½ years.

To all whom it may concern:

Be it known that I, COSIMO MITRANO, a citizen of the United States, and a resident of the city of New York, borough of Brooklyn, in the county of Kings and State of New York, have invented a new, original, and ornamental Design for Lockets, Fobs, or Similar Articles, of which the following is a specification, reference being had to

the accompanying drawing, forming part thereof.

The figure is a front elevation of a locket, fob, or similar article, illustrating my new design.

I claim:

The ornamental design for a locket, fob, or similar article, as shown.

COSIMO MITRANO.
